UNITED STATES PATENT OFFICE

ISIDOR KITSEE, OF PHILADELPHIA, PENNSYLVANIA.

CIGAR.

No. 888,508.

Specification of Letters Patent.

Patented May 26, 1908.

Application filed October 14, 1905. Serial No. 282,819.

To all whom it may concern:

Be it known that I, ISIDOR KITSEE, of the city and county of Philadelphia and State of Pennsylvania, have invented certain new and useful Improvements in Cigars, of which the following is a specification.

My invention relates to an improvement in cigars. Its object is to provide the cigar with a device whereby its particular brand 10 may be easily ascertained, and it is also the aim of my invention to produce through said device an air-channel through said cigar.

In the drawings, Figures 1 and 2 are side elevations of a cigar provided with the device 15 embodying my invention.

It is the essential feature of this my invention that throughout said cigar is carried a thread, and that preferably the ends of said thread shall extend outside of said cigar. In 20 Fig. 1 the ends of this thread are left free but in Fig. 2 the ends of the threads are connected in a manner so as to form a knot or bow about midway of the length of the cigar.

The cigar proper is designated as A, the 25 thread or fiber as B; this thread may be applied to the cigar during the process of forming said cigar, which I prefer, but it may also be applied to the cigar after the same is made.

30 I exclude distinctly from this my inven-

tion all and everything whereby brands of cigars are distinguished from each other through fibers either in the shape of threads or otherwise placed only around the cigar, or going only part way through the body of the 35 cigar, as the same have proven unsatisfactory.

Having now described my invention, what I claim as new and desire to secure by Letters Patent is:—

1. A cigar, a thread passing lengthwise throughout the whole body of the cigar, the ends of said thread forming a loop on the outside of said cigar.

2. In combination with a cigar, a thread 45 passing lengthwise through the whole body of said cigar, the ends of said thread connected together on the outside of said cigar.

3. A cigar, a thread carried lengthwise through the whole body of said cigar, the 50 ends of said thread being carried about midway outside of said cigar, forming there a loop around the circumference of the cigar and being connected after forming said loop.

In testimony whereof I affix my signature 55 in presence of two witnesses.

ISIDOR KITSEE.
